US0D1027424S

(12) **United States Design Patent** (10) Patent No.: **US D1,027,424 S**
(45) Date of Patent: ** May 21, 2024

(54) **KEY RING**

(71) Applicant: **Shenzhen Zhongchuangxunda Technology Co., Ltd.**, Shenzhen (CN)

(72) Inventor: **Yuanhui Zhang**, Shenzhen (CN)

(**) Term: **15 Years**

(21) Appl. No.: **29/818,924**

(22) Filed: **Dec. 10, 2021**

(51) LOC (14) Cl. **03-01**

(52) U.S. Cl. **D3/207**
USPC .....

(58) **Field of Classification Search**
